(57) **CLAIM**

The ornamental design for a C-clamp, as described and shown.

DESCRIPTION

FIG. 1 is a side view of the C-clamp of this invention; FIG. 2 is a front view of the C-clamp shown in FIG. 1 and adding, for environmental purposes, a dotted line representation of a length of pipe (shown in cross section) gripped between the inner end of the bolt and the serrated portions on the body of the C-clamp;

FIG. 3 is a side view of the C-clamp, looking at the side opposite that shown in FIG. 1;

FIG. 4 is a top plan view of the C-clamp; and,

FIG. 5 is an inverted plan view of the C-clamp.

The opposite side of FIG. 2 is a mirror image thereof.
